ASH RECEPTACLE AND ASSEMBLY

John Visser, Grand Rapids, Mich., assignor to
F. L. Jacobs Co., Detroit, Mich., a corporation
of Michigan

Application November 17, 1938, Serial No. 240,943

9 Claims. (Cl. 206—19.5)

This invention relates to an ash receptacle and ash receptacle assembly.

In the design and construction of ash receptacles, and particularly ash receptacles which are designed to be mounted on a metal panel or plate member such as the instrument panel of an automobile or other vehicle, it is highly important that the assembly be decorative in its external appearance, be rugged and reliable in use, be substantially free from vibration and noise, be economical to manufacture and simple to assemble.

Accordingly, it is an object of the present invention to provide a novel ash receptacle and ash receptacle assembly which possesses the above highly desirable characteristics.

Another and further object of the present invention is to provide a novel ash receptacle assembly including an ash-receiving box, a decorative panel, and a knob which are secured together in a novel manner.

Another and still further object of the present invention is to provide an ash-receiving box having a frusto-conical recess in a front wall thereof and having a decorative panel disposed over the front wall of the box, a complementary frusto-conical raised portion on the panel being arranged to be seated in the frusto-conical recess of the box and in which a single detachable fastening element secures the panel to the box and also secures a knob on the front face of the panel.

The novel features which I believe to be characteristic of my invention are set forth with particularity in the appended claims. My invention itself, however, both as to its organization and manner of construction, together with further objects and advantages thereof, may best be understood by reference to the following description, taken in connection with the accompanying drawing, in which:

Figure 1 is a side elevational view, partly in cross section, of the ash receptacle and ash receptacle assembly taken along the line I—I of Figure 2;

Figure 2 is a rear elevational view, taken along the line II—II of Figure 1, of the ash receptacle and ash receptacle assembly; and

Figure 3 is a top sectional view, taken through the curved plane as indicated by the section line III—III of Figure 1.

The ash receptacle assembly illustrated in the various figures of the drawing comprises, in general, a supporting frame 10 having a substantially rectangular opening 11 therein within

which an ash receptacle 12 is mounted for a limited angular movement therethrough. The support or mounting frame 10 is arranged to be mounted on a substantially vertically disposed plate or panel member 13. It will of course be understood that the panel member 13 may be the principal panel member on which the ash receptacle assembly is to be mounted, or it may comprise an auxiliary panel member or support there placed which is adapted to be secured to the main or principal panel.

In addition to the rectangular aperture 11 provided in the mounting frame 10, a second aperture may also be provided which is defined by a frusto-conical inturned lip or flange portion 14. It has been found desirable to provide the mounting frame 10 with this second apertured portion for the purpose of receiving other auxiliary equipment (not shown), such, for example, as a cigar or cigarette lighter construction either of the removable plug type or of the self-lighting socket type in which a cigar or cigarette is merely inserted into a cylindrical socket member where it is automatically lighted.

The frame or mounting member 10 is provided with a rearwardly and downwardly extending curved cover portion 15 which is arranged to extend over the opened upper end of the ash-receiving box or receptacle 12 when the latter is in its closed position. As is shown in Figure 1 of the drawing, the cover member or portion 15 is provided with an upturned forward lip 16 which is arranged to bear against the rear face of the main portion of the frame or supporting member 10. The principal or front portion of the frame construction 10 is provided with an integral rearwardly bent tongue or lip 17 which extends back under the forward edge of the cover member or portion 15. The cover member 15 is spot-welded soldered, or otherwise suitably secured to the frame member 10.

In order that the ash receptacle 12 may be supported in the frame 10 in a manner to permit angular or rocking movement into and out of the opening 11 of the frame 10, a portion 18 of the stock which is cut away in forming the aperture 11 in the frame 10 is left integral with the frame 10 along the lower edge 19 of the aperture 11. This portion 18 is bent rearwardly and downwardly in a curved surface, which, as will presently be pointed out, comprises a support and bearing surface for the ash receptacle 12.

A second integral and smaller tab or tongue 20 is also struck from the frame member 10, it being left integral with the latter along its lower

edge. The tab or tongue 20 is bent obliquely rearwardly and upwardly and is arranged to be seated on and detachably secured to a complementary lip portion 21 of the panel or support plate 13. As is shown in Figure 1 of the drawing, the detachable connection between the tongue 20 and the lip portion 21 may be made by a nut and bolt 22 or in any other suitable manner.

The ash receptacle 12 which is adapted to be mounted in and supported by the frame member 10 comprises in general an ash-receiving box 23, a decorative panel 24 and a knob 25. The ash-receiving box 23 is preferably formed of a plurality of sheet metal parts which are spot-welded or otherwise suitably secured together. More particularly, the ash-receiving box 23 includes a pair of side walls 26, and a sheet metal strip 27 which is bent to form a front and a rear wall 28 and 29, respectively, and a bottom 30 a portion of which is transversely curved as at 31 to form a surface complementary to the bearing surface 18. The side walls 26 are provided with turned flanges 32 which are bent over the adjacent edges of the strip 27 and spot-welded or otherwise suitably secured thereto.

In order to minimize frictional wear on the side walls of the ash receptacle 12, the top edges of the side walls 26 are provided with a spacing rib 33. The spacing ribs may be conveniently formed by bending the upper marginal portion of each side wall 26 outwardly slightly and then by terminating it in an inturned curled edge portion. The top edges of the side walls 26 are of course longitudinally curved so as to be complementary to and lie under the curved cover member 15 of the frame and supporting structure 10.

As is shown in Figures 1 and 2 of the drawing, the bottom edge of each side wall 26 is inturned to underlap the bottom portion 30 of the strip 27, as is indicated at 34. That portion of the inturned flange 34 which underlaps the transversely curved portion 31 of the bottom of the ash receptacle 12, in addition to its function of providing a seal between the side walls 26 and the bottom 30, also provides a bearing rib which is arranged to ride over the bearing surface 18. Since this reduces the bearing area of the ash receptacle 12 on the curved bearing surface 18, it is clear that friction is greatly minimized.

As will be apparent to those skilled in the art, means must be provided for maintaining the ash receptacle 12 in engagement with the bearing surface 18 during the normal opening and closing operation of the ash receptacle into and out of the supporting frame 10. This means is illustrated as a spring-biasing arrangement which engages the curved cover member 15 and forces the bearing rib portion 35 of the underlapping flanges 34 into engagement with the bearing surface 18 and maintains this engagement throughout a movement of the ash receptacle 12 from the full-line position as shown in Figure 1 to the dotted-line position as shown in Figure 1.

The spring-biasing means includes a spring member 36 having a configuration similar to that shown in Figures 1 and 3 of the drawing. This spring member 36 is secured to the rear wall 29 of the ash receptacle 12 in some suitable manner, such, for example, as by spaced locking ears 37, there being preferably at least two on each side of the spring member 36. The spring member 36 includes a base portion 38 which lies flush

against the rear wall 29 of the ash receptacle 12 and a free intermediate portion 39 which extends rearwardly from the base portion 38, upwardly substantially parallel to the rear wall 29, and then obliquely upwardly and forwardly to a point above and approximately over the top edge of the rear wall 29. The intermediate portion 39 thereafter merges into a snuffer portion 40 which is provided with a slightly cup-shaped and apertured central portion 40' into which the lighted end of a cigarette or cigar may be pressed to extinguish it.

Upon a close inspection of Figure 1 of the drawing, it will be observed that there is an abrupt connecting portion 41 between the intermediate portion 39 of the spring member 36 and the snuffer end portion 40. The high point 42 of the spring member 36 is arranged to bear against a pair of parallel spaced bearing ribs 43 which are formed in the cover member 15. These spacing or bearing ribs 43, as will be clear to those skilled in the art, greatly reduce frictional wear between the spring member 36 and the cover member 15.

To limit the outward movement of the ash receptacle 12, the central portion of the inturned flange 17 of the supporting frame 10 is pressed downwardly as at 44 to form a stop which will abut the portion 41 of the spring member 36 as the ash receptacle 12 is rocked outwardly in the frame 10.

In order to completely remove the ash receptacle 12 from the supporting frame 10, it is merely necessary to depress the snuffer or end portion 40 of the spring member 36 to an extent sufficient to permit the high point 42 of the spring element 36 to pass below the stop 44. The ash receptacle 12 may then be readily removed from the supporting frame 10. In reassembling the ash receptacle 12 in the supporting frame 10, the transversely curved portion 31 of the base 30 is disposed over the bearing surface 18 of the support, and the ash receptacle 12 is then rocked into its closed position, the high point 42 of the spring member 36 being cammed under the stop 44 of the frame 17.

The novel ash receptacle and ash receptacle assembly, including the ash-receiving box 23, the decorative panel 24 and the knob 25, and the manner in which these elements are secured together will now be discussed. The front wall 28 of the ash-receiving box 23 has pressed therein in its upper portion a frusto-conical recessed portion 45 which includes a base portion 46 and a frusto-conical side wall 47. The decorative panel or plate 24, which is designed to extend over the front wall 28 of the ash-receiving box 23, is also provided with a frusto-conical raised portion 48 which is complementary to the frusto-conical recessed portion 45 of the ash-receiving box 23. This frusto-conical raised portion 48 on the rear face of the decorative panel 24 is preferably pressed or stamped in the panel so as to form a frusto-conical recessed portion on the front face of the decorative panel 24 which includes a base portion 49 and a frusto-conical side wall portion 50.

A knob 25 is provided for the structure, which is shown by way of example in Figures 1 and 3 of the drawing, as in the form of a transverse partition which extends across the frusto-conical recessed portion 48 and which is provided with converging end walls which permit the knob to be seated on the conical side wall 50 of the recessed portion 48. The knob 25 is given any

desired ornamental configuration. One form of ornamentation which has been found pleasing to the eye is to provide a depressed portion 51 on either side of the knob 25 and to provide the 5 front face 52 of the knob with a slightly convexed curvature from top to bottom. A groove or indentation is also illustrated in the front face 52 of the knob 25 as at 53.

The knob 25 may be formed of any suitable material but is preferably formed of some suitable molded material, since such a material permits easy ornamentation thereof at minimum cost. Imbedded in the base of the knob 25 is an internally threaded sleeve 53 which is arranged 10 to receive the threaded shank of a fastening element or bolt 54 which extends through suitable confronting apertures in the base portions 46 and 49 of the frusto-conical portions 45 and 48, the head of the bolt 54 being arranged to 15 engage the rear face of the base 46 of the frusto-conical portion 45. It will thus be seen that the bolt 54 not only secures the knob 25 to the ash-receiving box 23, but also secures the decorative panel 24 since the panel lies between the ash-receiving box 23 and the knob 25. It will also be 20 apparent that, due to the fact that both the front wall 28 of the ash-receiving box 23 and the decorative panel 24 are provided with complementary frusto-conical portions, the decorative panel 24 is positioned and located on the front 25 face of the ash-receiving box 23. That is to say, transverse translational movement of the panel 24 with respect to the front wall 28 of the ash-receiving box 23 is prevented by virtue of the 30 fact that the frusto-conical portion 48 of the decorative panel 24 is seated in the frusto-conical portion 45 of the ash-receiving box 23. Outward separation of the panel 24 from the ash-receiving box 23 is prevented by virtue of the 35 fastening element or bolt 54 which extends through the front wall 28 of the ash-receiving box 23 and the decorative panel 24 into threaded engagement with the knob 25. There only remains, therefore, to provide some means for preventing relative rotation between the ash-receiving box 23, the decorative panel 24 and the knob 25. This may be conveniently provided by 40 forming a lock pin 55 on the base of the knob 25 at a point spaced from the internally threaded 45 sleeve 53. The lock pin 55 is arranged to extend rearwardly through a set of confronting recesses in the base portions 46 and 49 of the frusto-conical portions 45 and 48, respectively. Since the lock pin 55 is displaced from the only possible axis of relative rotation of the ash-receiving 50 box 23, the decorative panel 24 and the knob 25, it is clear that the lock pin 55 will prevent relative rotation of these parts.

To augment the securing engagement between 55 the decorative panel 24 and the ash-receiving box 23 provided by the fastening element 54, a pair of interlocking lips or tongues 56 and 57 are provided at the lower ends of the front wall 28 and the decorative panel 24, respectively. More 60 particularly, a downwardly extending tongue or lip 56 is spot-welded or otherwise suitably secured to the front wall 28 of the ash-receiving box 23, and an upturned integral lip or tongue 57 is turned upwardly from the lower edge of the decorative panel 24. The lip 56 is arranged to 65 extend down into the hook-shaped lip 57 and be seated therein.

To assemble the decorative panel 24 on the front wall 28 of the ash-receiving box 23, the upturned lip 57 is hooked under the downwardly extending 70

tongue 56 and the upper portion of the decorative panel 24 is thereafter rocked into engagement with the front face of the ash-receiving box 23. As the decorative panel 24 is rocked into position against the front face of the box 23, 5 the frusto-conical portion 48 of the panel 24 is nested and seated in the frusto-conical portion 45 of the front wall 28 of the ash-receiving box 23. The knob 24 is then moved into position in the frusto-conical portion 48, the lock pin 55 10 being guided into the confronting apertures provided therefor in the base portions 46 and 49 of the frusto-conical portions 45 and 48, respectively. The fastening element or bolt 54 is then inserted through the other set of confronting 15 apertures provided in the base portions 46 and 49 and is threaded into the sleeve 53 and tightened until the knob 25 and the decorative panel 24 are snugly and firmly held over the front wall 28 of the ash-receiving box 23. 20

In order to further enhance the general appearance of the ash receptacle 12 and the assembly and mounting therefor, the mounting frame 10 is constructed so that its front or principal portion is in the form of a bezel. That is to say, the front face of the frame member 10 is provided with a depressed flange 58 around its entire marginal portion and slightly spaced from its outer peripheral edge. That portion of the bezel which lies opposite the decorative panel 24 30 of the ash receptacle 12 is adapted to receive and seat the decorative panel 24 when the ash receptacle 12 is in its closed position. The peripheral edge of the decorative panel 24 is preferably inturned around its entire periphery as at 35 59 to provide an edge which can be conveniently and snugly seated on the bezel 58. That portion of the bezel which lies above the top edge of the decorative panel 24 is arranged to receive and seat some auxiliary smoking accessory or other 40 equipment (not shown).

The bezel construction of the supporting frame 10, as will be apparent to those skilled in the art, permits a flush fitting of the front face of the ash receptacle 12 and also of any auxiliary equipment which is mounted on the frame 10 above the ash receptacle 12. 45

The outer peripheral edge of the frame 10 is preferably bent rearwardly as at 60 in order to bear against the plate or panel member 13. The 50 front-faced portion 61 which lies between the recessed flange 58 and the rearwardly bent peripheral edge 60 may be ornamented in any suitable manner which will enhance the general appearance of the assembly. 55

As shown in Figure 2 of the drawing, the frame member 10 is provided with two slots 62 through which a frame member attaching tongue carried by the main supporting structure 13 may be inserted and bent down to augment the detachable 60 connection made by the nut and bolt unit 22 which secures the tongue 20 to the lip 21. These slots 62 may, however, be omitted and the frame 10 secured to the panel 13 in any other suitable manner. 65

While I have shown a particular embodiment of my invention, it will of course be understood that I do not wish to be limited thereto, as many modifications may be made, and I therefore contemplate by the appended claims to cover all 70 such modifications as fall within the true spirit and scope of my invention.

I claim as my invention:

1. An ash receptacle comprising an ash-receiving box having a recessed portion in the front 75

JOHN WESSE
